his Attorney.

UNITED STATES PATENT OFFICE.

FLORRENCE S. O'BRIEN, OF ST. PAUL, MINNESOTA.

COMBINED SALT AND PEPPER SHAKER.

Application filed October 24, 1921. Serial No. 509,856.

To all whom it may concern:

Be it known that I, FLORRENCE S. O'BRIEN, a citizen of the United States, residing at St. Paul, in the county of Ramsey and State 5 of Minnesota, have invented a new and useful Improvement in Combined Salt and Pepper Shakers, of which the following is a specification.

My invention relates to salt and pepper 10 shakers and has for its object to provide a single container in which both salt and pepper may be contained at the same time.

Another object is to provide means for simultaneously regulating the amount of 15 either the salt or pepper discharged from the shaker.

Another object is to provide means for increasing the amount of pepper discharged as the salt is decreased and vice versa.

20 A still further object is to provide means for preventing the escape of ingredients within the container through openings other than those intended for the purpose.

Another object of the invention is to provide 25 a movable partition within the shaker adapted to divide the interior thereof into two compartments.

Another object is to form the closure cap 30 with a member adapted to engage said partition as the device is applied so as to rotate the partition with the said cap and so hold the same in proper relation thereto regardless of the position of the cap and the container.

Another object is to provide a number of 35 openings on either side arranged in crescent shaped formation, and a closure member adapted to swing from one side to the other to close either of said sets of openings.

The full objects and advantages of my 40 invention will appear in connection with the detailed description thereof and are particularly pointed out in the claims.

In the drawings, illustrating the application 45 of my invention in one form: —

Fig. 1 is a vertical sectional view of my improved invention.

Fig. 2 is a bottom view of the cap used in connection with my salt and pepper shaker.

Fig. 3 is a side elevational view of the cap 50 and a portion of the salt and pepper shaker shown in Figure 1.

Fig. 4 is a fragmentary sectional view similar to Figure 1 showing another form of the invention.

Fig. 5 is a view similar to Figure 4 taken 55 at right angles thereto.

In the form of the invention shown in Figures 1, 2, and 3, I have shown an ordinary form of salt and pepper shaker 10 which may be of glass, pewter, or any other 60 suitable material and which forms a container for the ingredients to be placed within the same. This container is formed with a straight uniform cylindrical bore 11 which extends throughout the length of the same. 65 Within the interior of the container 10 is positioned a vertical partition 12 which snugly fits within the bore 11 and extends flush with the top 13 of container 10 as indicated at 14 in Figure 1 so that the whole 70 container and partition terminate in a flat surface. The partition 12 is preferably constructed out of cork or some other absorbent material which when the salt is placed within the container serves to absorb some of the 75 moisture from the salt and cause the same to flow freely. Although I have found cork to work very satisfactory other substances may be used in place thereof which operate 80 in a similar manner. With this construction two semi-cylindrical compartments 15 and 16 are provided in which the salt and pepper may be placed when the cap is removed from the container 10.

The cap for closing the opening in container 10 is indicated in its entirety at 17 and comprises a planular top portion 18 and a flanged portion 19 which is threaded at 20 as to screw upon threads 21 formed on the neck 22 positioned on the upper portion of 90 container 10. The planular portion 18 of cap 17 is provided with a plurality of openings 23 on one side and a similar set of openings 24 on the other side, which openings are arranged in the shape of a crescent 95 and are positioned to register with the openings in container 10 leading to the compartments 15 and 16. This arrangement of the holes gives a more uniform distribution of the ingredients when the shaker is used. If 100 both sets of the openings 23 and 24 are uncovered, both salt and pepper may be shaken from the shaker at one time.

The device for regulating the amounts of the ingredients discharged through the cap 17 consists of a plate 25 which is pivoted by means of a rivet 26 to one side of the planular portion 18 of said cap. This plate is 105

formed with two arcuate portions 27 and 28 which are adapted to cover the openings 23 and 24 as the said plate 25 is oscillated from side to side on its pivot 26. For moving the 5 said plate I provide a lever 29 which issues outwardly from the said plate 25 and protrudes through a slot 30 formed in the flanged portion 19 of cap 17. As the protruding end of the lever 29 is manipulated 10 by the finger, plate 25 may be oscillated to completely cover either sets of the holes 23 and 24 or to partially cover both of them. By varying the position of the said plate the 15 respective number of holes uncovered on each side may be varied at will so that the exact proportion of the ingredients discharged will be changed to suit the requirements.

To prevent the ingredients from discharging through the slot 30 I form the interior of the cap 17 with an annular shoulder 31 extending around the same, which shoulder is of the same thickness as the plate 25 and fits upon the upper surface 13 of container 10. This shoulder is cut away at 32 to permit the lever 29 to extend outwardly through cap 17. In said shoulders are formed two notches 33 and 34 which are provided with arcuate surfaces 35 being described about 20 the pivot 26 as a center. These surfaces are adapted to cooperate with an arcuate surface 36 formed on two lugs 37 and 38 issuing outwardly from the plate member 25. When the device is in a position indicated in Figure 2 the extreme end of lug 37 engages the beginning of the arcuate surface 35 while the remainder of the surface 36 is in contact with the surface 35 of notch 34. As the plate 25 is oscillated surfaces 35 and 36 are constantly in engagement. After the cap has 40 been screwed down, the surface 13 of the container 10 covers the opening 32 in shoulder 31 so that the slot 30 is completely closed from the interior of the container thereby preventing the passage of any of the ingredients outwardly through said slot.

In order to have the partition 12 positioned properly relative to the openings 23 and 24 in the cap 17, I provide the said cap with a downwardly depending lug 37 which is adapted to engage the upper portion of the partition 12 near the edge thereof so that as the said cap is screwed down, said lug engages the said partition and causes the same to rotate. In this manner 50 the partition 12 is constantly held in the proper relation to the said cap so that proper ingredients are at all times discharged through the respective openings 23 and 24.

In Figures 4 and 5 I have shown a modification of the invention in which the cap 17 is formed without the flange 19 indicated in the other form. In place of the 65 same I provide a threaded sleeve 40 which

has an inwardly turned flange 41 adapted to ride upon the outer periphery of a flange 42 formed on said cap below the slot 30 through which the lever 29 passes. In this construction the partition 12 is made to 70 project above the upper surface 13 of container 11 as indicated at 50 in Figure 5 so that the two compartments 15 and 16 are still separated from one another. In using this device the planular portion 18 75 which is formed with a pair of downwardly depending lugs 43 and 44 is placed directly over the partition 12 with the lugs 43 and 44 straddling the partition. Sleeve 40 is then screwed in place upon cap 17 80 until the flange 41 is firmly fitted upon the edge 42 thereof, the same then firmly holding the device in place.

The advantages of my invention are manifest. The device is extremely simple and 85 can be constructed at a small cost. The annoyance in having two devices for dispensing two commodities which are almost always used is eliminated thereby saving time and annoyance. The device is very effective 90 in operation and does not easily get out of order.

In accordance with the patent statutes I have described the principles of operation of my invention together with the apparatus which I now consider to represent the best embodiment thereof, but I desire to have it understood that the construction shown is only illustrative and that the invention can be carried out by other means 95 and applied to uses other than those above set forth within the scope of the following 100 claims:

I claim:—

1. A combined salt and pepper shaker 105 comprising a receptacle having two compartments, a cap mounted on said receptacle, an imperforate plate pivoted to said cap at one end thereof, said plate having arcuate portions of a radius substantially equal to that of the cap, and being adapted to swing from one side of the periphery of said cap to the other, and holes in said cap arranged on both sides of said plate along the periphery thereof in crescent shaped formation to communicate separately with said compartments.

2. A combined salt and pepper shaker comprising a receptacle, a cap mounted on said receptacle, said cap having a planular top, a plate having arcuate portions pivoted to said cap near the periphery thereof, a slot in said cap, a lever issuing outwardly from said plate and passing through said slot for oscillating the plate, a partition in said receptacle forming two compartments, sets of openings formed in said cap positioned on each of the arcuate portions thereof and arranged in crescent shaped formation, a shoulder issuing out- 125

wardly from said cap of a depth the same as said plate extending around the periphery of the same, notches formed in said shoulder having arcuate surfaces described about the pivot of said plate as a center, lugs formed on said plate having arcuate surfaces adapted to cooperate with said ar-

cuate surfaces on said shoulder to form a closure between said slot and the interior of said receptacle. 10

In testimony whereof I affix my signature.

FLORENCE S. O'BRIEN.
